(57) **CLAIM**

We claim the ornamental design for a fitness band spine, as shown and described.

DESCRIPTION

FIG. 1 is a front view of a fitness band spine.

FIG. 2 is a rear view of the fitness band spine of FIG. 1.

FIG. 3 is a side view of the fitness band spine of FIG. 1; the opposing side view of the fitness band spine is a mirror image of FIG. 3 and is not shown separately.

FIG. 4 is a top view of the fitness band spine of FIG. 1.

FIG. 5 is a bottom view of the fitness band spine of FIG. 1.

FIG. 6 is an off-angle view of the fitness band spine of FIG. 1; and,

FIG. 7 is another off-angle view of the fitness band spine of FIG. 1.

A fitness band spine for a band portion of a wearable fitness band system is shown in the accompanying figures.

Stipple shading has been provided to illustrate surface contours and does not indicate texture. The broken lines shown in the drawings illustrate portions of the fitness band spine that form no part of the claimed design. Surfaces that do not include stipple shading form no part of the claims design.

The fitness band spine is flexible so that it may be worn on a person's wrist when in use.
